UNITED STATES PATENT OFFICE.

RICHARD H. SHADRICK, OF MINNEAPOLIS, MINNESOTA, ASSIGNOR TO ANDREW E. CARLSEN, OF MINNEAPOLIS, MINNESOTA.

THERMOSTATIC CUT-OUT FOR GAS VALVES.

Application filed August 14, 1925. Serial No. 50,246.

This invention relates primarily to attachments for gas heaters of hot water heating systems, and the main object is to provide a novel, efficient and practical device for preventing the gas valve from being opened when the pilot light of the burner has gone out so that gas will not pass through the burner of the heater when there is nothing to ignite it. Further and more specific objects will be disclosed in the course of the following specifications, reference being had to the accompanying drawings, wherein:

Figure 1 is a perspective view, partly in section, of a device embodying my invention. 15 Figure 2 is a detail elevation of the gas valve operating mechanism, with portions broken out for purpose of illustration.

Figure 3 is a sectional elevation similar to Figure 2, but showing the valve mechanism as in its tripped or off position. 20

Figure 4 is a cross section as on the line 4-4 in Figure 2.

Figure 5 is a sectional view as on the line 5-5 in Figure 2, fractional portions being 25 broken away.

The heater, gas connections and gas valve actuating mechanism illustrated in the drawings is substantially similar to the corresponding elements shown in my co-pending 30 application for patent, Serial No. 734,180, filed on August 26th, 1924, for heater control, and may be described as follows:

A designates the casing of a heater having a burner B, and a coil C, which is circuitously connected with a storage tank (not shown), the water of which is circulated through and heated in the coil C by the flame from the burner B. The burner B is supplied with gas by a pipe E, into which is cut the 35 valve F. This valve F is of a standard type in which a valve plug 6 is yieldingly held in a closed position by a spring 7 and is adapted to be opened by the depression of a stem 8 which slidably projects, through a suitable 40 packing joint 9, to the exterior of the valve body proper. A small valve 10, which is connected with a pilot light 11 (adjacent to the burner B) by a tube 12, is secured to the valve F, and communicates with the intake 45 side thereof so that the pilot will be kept burning at all times, and thus be in readiness to light the heater burner whenever the main gas valve 6 is opened.

Rigidly secured upon the valve F is a casing G having a standard or partition 13, provided at its upper end with an extension 14. Slidably journaled in the standard 13 and in a plate 25, adjacent the end wall 16 of the casing G, and directly over the valve stem 8 is a shaft 17, the outer end of which is angularly bent, as at 18, whereby the shaft may be oscillated. The shaft 17 is provided with a cam 19, which is normally positioned directly over the pin 8, and is yieldingly retained in that position by a spring 20. A suitable stop such as an enlargement or shoulder 21 of the shaft 17 prevents the cam from being moved inwardly from the pin or stem 8, but as the shaft 17 is slidably journaled in the casing, it may be moved outwardly, against the tension of the spring 20, until the cam misses the stem. This outward movement is accomplished by a diaphragm 22, so as to render the cam ineffective even when the shaft 17 is oscillated, but this mechanism is more fully disclosed and claimed in the above mentioned application Ser. No. 734,180, and is therefore not here shown or described in detail.

Under normal or idle conditions, the valve 6 is closed, and the arm 18 is in a downward position, being held so by suitable means such as a weight W, (see Fig. 1). The arm 18 is elevated and the valve 6 is opened (by the action of the cam 19) by a pull chain or cable 24, which leads to a remote point or station, located for instance as in a kitchen or bath room, and thus the burner is lighted, it being understood, that the pilot light 11 is lit. It is found, however, that pilot lights such as shown as 11, are not always dependable and will occasionally go out, either because of drafts, or due to the accumulation of carbon, and for other reasons: and under such circumstances, it will be seen that unless there is some way of notifying the operator, the gas flowing through the burner will not be ignited and will escape with possibly dangerous consequences.

To overcome the objections last above mentioned, I slightly alter the construction shown in my previously mentioned application, and provide, in addition thereto, a thermostatically controlled mechanism for rendering the valve actuator inoperative when the pilot light, for any reason, goes out.

Thus, instead of journaling the outer end of the shaft 17 directly in the wall 16, I journal it in a bearing plate 25, which is slidable with respect to and yieldingly held against the wall by the spring 20. The wall is then provided with a slot 26 through which the shaft extends and which permits a slight up and down movement of the outer portion of the shaft. The wall 16 is also provided with a second slot 27 through which a lip 28 of the plate 25 extends and is guided.

The lip 28 is normally engaged and held down by a hook 29 of a lever 30 which is pivotally secured, as at 31, on the wall 16. A spring 32 is associated with the lever 30 in such a manner as to tend to disengage the hook 29 from the lip 28, but this engagement is normally maintained by a wire or cable 33, the upper end of which is secured to a lever 34.

The lever 34 is pivoted, as at 35, to a post 36 which is carried by a frame member 37, secured on the heater casing A by a bolt 38. Rigidly secured to the post 36 is a bar of heat conducting material 39, the inner end of which extends into the casing A immediately above or adjacent to the pilot tip 11 so that it will be heated thereby. The outer end of the bar 39 may be slightly adjusted by a set screw 40. Adjacent to the bar 39 and with its inner end secured thereto is a strip 41 of what is commonly known as "thermostatic metal", which quickly changes its shape under different temperatures.

When the pilot light 11 is lit so that the heat imparted by the bar 39 to the member 41 is within certain limits, the strip 41 will be in the full line position shown in Figure 1, and when in said position, the strip 41 engages a trigger member 42, pivoted at 43, and prevents it from being swung inwardly. The lower end of the member 42 has a hook or finger 44 which normally engages the outer end of the lever 34 and prevents it from being pulled downwardly by the wire 33.

When the pilot light, for any reason, goes out, it will be seen that as the bar 39 cools the strip of thermostatic metal 41 will also cool and will retract upwardly to the dotted line position. And when this occurs the trigger 42 will swing inwardly and will release the lever 34 and connection 33, allowing the spring 32 to disengage the hook 29 from the lip 28. Now if the operator pulls the chain or cable 24 to light the heater, the cam 19 will not press the valve stem down to open the valve, but will merely raise the shaft 17 and plate 25 to the position shown in Figure 3, thus leaving the valve closed. If the operator does not notice the absence of the resistance by the spring 7, when he pulls the pull chain, he will soon find that something needs adjustment as there will be no hot water in response to the usual light-

ing operation. It will then be necessary for him to relight the pilot and restore the various parts to their positions as shown in Figure 1 of the drawing. It may here be noted that a set screw 45 is arranged for adjusting the angle or position of the strip 41 with respect to the bar 39. It may also be noted that the entire thermostatic mechanism, with the exception of the inner end of the bar 39, is located outside of the heater casing, the object being to prevent the mechanism from being damaged or distorted by the intense heat of the main burner B.

It is understood that various modifications may be made in the general design and structural details of the invention as herein illustrated and described, providing, however, that such modifications come within the spirit and scope of the appended claims. Having now, therefore, fully shown and described my invention, what I claim to be new and desire to protect by Letters Patent is:—

1. The combination with a heater, having a main burner and a pilot burner, of a valve to control the supply of gas to the main burner, a rotatable cam having a cam face normally held in engagement with the valve to open and close the same, means for manually actuating the cam, and thermostatically operated means influenced by the pilot burner for releasing the cam from its normal position so as to render it ineffective for opening the valve.

2. The combination with a heater, having a main burner and a pilot burner, of a valve to control the supply of gas to the main burner, a rotatable cam having a cam face normally held in slidable engagement with the valve to open and close the same, a movable bearing member for normally retaining the cam in its operating position, and a thermostatic mechanism associated with the pilot burner and said bearing member for releasing the latter from its normal position when the pilot burner is extinguished.

3. The combination of a main burner, a pilot burner, a valve for controlling the supply of fuel to the main burner, an oscillatable cam for opening and closing the valve, a bearing member for holding the cam in its operative position, said bearing member being releasably secured in an initial or operative position by a catch member, and means associated with the pilot burner to withdraw the catch and release the bearing member whereby to render the cam ineffective for opening the valve.

4. The combination of a main burner, a pilot burner, a valve for controlling the supply of fuel to the main burner, an actuator for opening and closing the valve, a lever for normally retaining the actuator in an operative position, a trigger for holding the lever in its normal position, and a strip of ther-

- mostatic metal rigidly secured at one end near the pilot burner, so as to be influenced thereby, said trigger being arranged so as to releasably engage endwise against the opposite or movable end of said strip. 5. The combination of a main burner, a pilot burner, a valve for controlling the supply of fuel to the main burner, an actuator for opening and closing the valve, a lever 10 for normally retaining the actuator in an operative position, a trigger for holding the lever in its normal position, and a strip of thermostatic metal rigidly secured at one end near the pilot burner so as to be influenced thereby, said trigger being arranged so as to releasably engage the other end of the strip whereby it will be tripped to release the lever when the strip is contracted by being cooled. 15 6. The combination with a heater having a casing, and a main burner and a pilot burner within the casing, of a valve for controlling the supply of fuel to the main burner, an actuator for opening the valve, a heat conducting bar secured outside of and extending into the casing adjacent to the pilot burner, a temperature responsive element in contact with the bar portion outside the casing so as not to be subjected to the heat of the main burner, a tripping mechanism associated with the temperature responsive element and the valve actuator, whereby when the pilot burner is extinguished, the valve actuator will be rendered inoperative for opening the valve. 20 35 7. The combination with a heater, having a casing, and a main burner and a pilot burner within the casing, of a valve for controlling the supply of fuel to the main burner, an actuator for opening the valve, a heat conducting bar secured outside of and extending into the casing adjacent to the pilot burner, a temperature responsive element in contact with the bar and arranged entirely outside the casing, a tripping mechanism associated with the temperature responsive element and the valve actuator, said mechanism comprising a trigger, a lever releasably retained by the trigger, and a latch member connected with said lever. 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

valve for controlling the supply of fuel to the main burner, a rotatable actuator, a bearing for said actuator having primary and secondary positions, means for rotating the actuator whereby it will open the valve when the bearing is in said primary position, and thermostatically controlled means influenced by the pilot burner to effect a movement of the bearing to its secondary position, whereupon a movement of the actuator will be rendered ineffective for opening the valve.

15. The combination with a heater having a main burner and a pilot burner, of a valve

to control the supply of gas to the main burner, said valve having a projecting stem, an oscillatable cam acting member having a cam acting surface for engagement with the end of the stem, a latch for normally holding said cam member in an operative position, and thermostatically controlled means, influenced by the pilot burner, for releasing the latch to render the oscillatable member ineffective for opening the valve.

20 In testimony whereof I affix my signature.

RICHARD H. SHADRICK.
